FEEDING, PRINTING, AND CUTTING
MACHINE

Julius Rudie, St. James, Minn.

Application September 7, 1937, Serial No. 162,675

3 Claims. (Cl. 101—227)

This invention relates to improvements in feeding, printing and cutting mechanism and has, among its objects to provide a label printing and cutting device; to provide a compact device; to use rock levers as a means for operating the various mechanisms; to synchronize the movements of the levers from a single shaft; to provide a novel cutting mechanism, and means for operating the same; to provide a novel means for operating a printing mechanism; to provide a novel feeding mechanism and means for operating the same; to utilize the reciprocating type of printing mechanism, and to lever-actuate the same by symmetrical application of force.

15 Features of the invention include all details of construction shown, as well as the arrangement of the parts in relation to a specific type of printing mechanism; the arrangement of a supply holder about centrally of the machine to be surrounded by portions of the operating mechanism; and the broader ideas of means inherent in disclosure.

20 Objects, features and advantages of the invention will be set forth in the description of the drawings, and in said drawings:

Figure 1 is a vertical longitudinal section on line 1—1 of Figure 5, showing the printing head at its upper limit, but just ready to descend, see diagram Figure 7.

25 Figure 2 is a plan view partly in section with the mechanism positioned as in Figure 1.

Figure 3 is a vertical longitudinal section on line 3—3 of Figure 5, with a cutter at its upper limit just ready to descend, see diagram Figure 8.

30 Figure 4 is a vertical longitudinal section on line 4—4 of Figure 1, with the parts just ready to feed and with the printing head in raised position, see diagram Figure 9.

Figure 5 is a plan section on line 5—5 of Figure 3.

35 Figure 6 is a cross section on line 6—6 of Figure 3, with the knife and printing head in uppermost positions.

Figure 7 is a diagram showing the relations of 40 the lever-operating lugs of the lever-operating means, and corresponding to the position of Figure 1.

Figure 8 is a diagram showing the positions of 45 the lever operating lugs, and corresponding to their position in Figure 3.

Figure 9 is a diagram showing the positions of 50 the lever operating lugs, and corresponding to their position in Figure 4.

55 Referring first to Figure 5, the numeral 1 generally indicates a base or casing upon or within

which are arranged vertical longitudinally extending partition elements respectively indicated 2 and 3, see also Figure 6. These partition elements have horizontal bottom portions, 4, 5, having up-turned flanges 6 which are held by suitable fastening devices 7 to the outer casing 1. To the portions 4, 5 are attached rubber feet 9. The partitions 2 and 3 have upper horizontal flanges respectively designated 10—11, which act as supports for other parts of the mechanism. The vertical height of the plates 2 and 3 at the rear is greater than at the front as shown in Figure 1. Suitable spacer and brace bars for the plates are indicated at 15. The plates, with these bars, form a frame for the mechanism arranged transversely at the rear and journaled in suitable bearings of the plates 2 and 3 is a drive shaft 20 having a crank 21 and having thereon 4 discs respectively indicated 22, 23, 24 and 25. These discs constitute part of one kind of means for synchronizing the printing, cutting and feeding mechanisms. Discs 22 and 25 control printing and each has thereon a lug, said lugs being respectively designated 27 and 28. These lugs cooperate with levers respectively designated 30 and 31, pivoted as at 32 to the outer sides of plates 2 and 3.

The forward arms of the levers are connected with a printing mechanism, which is placed at the front of the machine. The illustrated printing mechanism per se is not claimed herein, but no limitation as to structure is intended. The relation of this specific type of mechanism to the other parts of the apparatus is claimed. Other reciprocating types or any type of printing mechanism which lends itself to operation by levers, is considered to be equivalent. In Figure 6 the forward arm or each lever 30—31 is shown pivotally attached to a forked fitting 35, which is in turn attached by a pin 36 to the lower end of a 40 plunger rod, 38, reciprocable in a guide 39 secured to and depending from the outturned portion 10—11 of the partitions 2—3. These rods are connected by their tops to the upper frame member 40 of a reciprocable type of printing 45 mechanism. When the rods are lowered by the levers, frame 40 engages frame 41, and lowers it to press bottom plate 42 against the material being printed. Arm 43 of frame 41 compresses springs 45, and the printing discs 46, pass through opening 47 of plate 42, and engage and print the material. The springs act automatically to restore frames 40 and 41 to the positions of Figures 4 and 6.

No detailed description is given of this well 55

known printing mechanism, which is used in hand numbering machines. It is understood, however, that other forms of printing mechanisms may be connected to and operated by the slide bars by means of levers and there is no intention to limit the invention entirely to the use of the specific printing device, although this specific device is claimed in combination with the means for operating it, and also in combination with the feeding and cutting mechanisms.

Referring to Figures 3, 4, the feeding mechanism includes a feed roll or disc 50 on a shaft 51 journaled, see Figure 5, in the partition plates 2 and 3. This disc 50 has a roughened surface, and the disc projects upwardly through a slot 54 of a feed table 65, see Figures 3 and 4. A roller 55 cooperates with the tape or material 56, a roll 57 of which is shown, to bring the material across the working surface of the disc 50, and this roll is mounted as best shown in Figures 2, 3 and 4 upon pintle 60 of a plate 61 which has upturned flanges pivoted upon a cross shaft 62, the shaft being mounted on lugs 63 which extend upwardly from the feed table 65. Coil springs 68 interposed between lugs 63, and the flanges of plate 61 act through the plate to urge the roller to operative position. The plate 61 is slotted for the reception of the roller 55 as shown in Figure 2, and pivotally associated with the plate 61 and pivoted by ears on laterally extending ends of pintle 60, is a gravity acting plate 70 weighted as at 71, and adapted to yieldably hold the material flat as it approaches the knife or cutting zone. The said feed table 65, is provided with a forwardly arranged pair of guide pins 73 and also with a rearwardly arranged pair of guide pins 74, see Figure 3. The latter pins are arranged on a downwardly rearwardly curved portion 75 of the table 65. The roller-carrying plate 61 has an upturned portion 78 cooperative with the down turned portion 75 of the feed table to form a receiving guide throat. The pivoting of the plate to the shaft of the presser roller 55 is a feature, and it is noted that by this means the rear end of the presser plate always follows the motions of the roller conformably to varying thickness of the material being fed. It is also noted that the forward end of the plate is near the cutting point so that proper holding of the material is assured at this point, it being noted again that the outer freely movable portion of this plate is weighted.

On the shaft 51 to which the feed disc 50 is attached is a ratchet wheel 80, see Figures 4 and 5, with the teeth of which a pawl 81 engages. This pawl is pivoted as at 82, to a rock lever 83, which lever is pivoted as at 84 to partition 2. A spring 85 urges the pawl to operative position. A detent 86 is cooperative with the teeth of the ratchet wheel to prevent reverse motion. Lever 83 is operated by lug 87 of disc 24 of shaft 20. Forwardly of the feed disc 50 is a platen roller 90 on which the material lies while being printed. This platen has a rubber facing. When feeding takes place this platen is rotated by means of a belt 91 and pulleys 92, 93, one pulley 92, being on the shaft 94 of the platen roll and the other pulley 93 being on the shaft 51 of the feed disc 50 and ratchet wheel 80. The printing discs 46, as before stated, move downwardly through the slot 47, see Figure 4, to engage and print the material lying on the platen. Attached to the plate 42 are a pair of spring fingers 42' which hold the material against the platen with sufficient pressure to insure positive

ejection by the platen, of the printed labels or tags from the machine.

Referring now to Figures 2 and 3; arranged between the feed disc 50 and platen roll 90 and cooperative with the forward edges of a plate 100, is a knife. This knife is so arranged that when it is pulled to its lowest position it cooperates with the outer edge 101 of the hardened insert plate 100 of the feed table 65, to shear off or cut the material. The knife 93 is connected by a link 102 with the forward arm of a lever 105 pivoted as at 106. When the lug 110 on the disc 23 engages and properly moves the lever, cutting occurs. The knife is pivoted as at 112 to lugs which rise from the hardened insert plate 100 the outer edge of which cooperates with the knife for shearing. These structural details, are features of the invention, along with the broader general combinations.

Referring to Figure 1; when the levers move from the full line position to the dot-and-dash line position, printing occurs. It is noted that each lever has a retraction spring 115, which yieldably resists movement of the lever by the lug. Thus, when action of the lug ceases the lever is caused to assume an initial position, in Figure 1 with the printing head fully raised, in Figure 3 with the knife fully raised and in Figure 4 with the pawl at its uppermost limit ready for a down stroke.

Referring to Figure 4 which shows the position of the parts at the beginning of feeding, see also Figure 9. On rotation of the shaft by the crank, in counter-clockwise direction, the ratchet mechanism is operated and the feed disc 50 is moved in counter-clockwise direction to feed the material to the position of Figure 3. In this figure printing is or has taken place, whereafter, on movement of the parts from their full to their dot-and-dash line positions see also Figure 8, cutting occurs. Thereafter the parts assume the position of Figure 4, and as feeding again occurs the cut off portion is moved by the platen through the opening 116 and into the hand of the operator, onto a table, or into some receptacle not shown.

It will be noted that the rock levers operate in parallel vertical planes which are perpendicular to the axis of rotation of the shaft 20. This is a feature which makes for compactness, ease of assembly, and simplicity. Another feature is the compact arrangement of a receptacle 120 for a supply roll of material to be printed, between certain of the mechanisms and the operating shaft, and flanked by the levers. It is noted, see Figure 5, that pairs of levers lie at opposite sides of this receptacle and that the receptacle lies below the top 121 of the top of the casing. Ordinarily a full roll (in this instance of paper tape) will project above the plane of the top of the casing. The top 121 of the casing is slotted as at 122 for introduction of the supply into the receptacle. The receptacle may be formed and supported in any suitable manner.

I claim as my invention:

1. In a machine for printing and cutting labels from a strip of tape, a rotary platen, means for intermittently feeding the tape to the platen, tension means for holding the tape in frictional contact with the platen during the printing operation, means for severing the tape, and means whereby the printed label is ejected from the machine by rotary movement of the platen, and as a result of said tension means holding the

severed label in feeding contact with the periphery of the platen.

2. In a machine for printing and cutting labels from a strip of tape, cutting and printing mechanisms, a rotary platen disposed beneath the printing mechanism and having means for driving it in timed relation thereto, and resilient elements for holding the severed label in frictional contact with the periphery of the platen, whereby rotary movement thereof will eject the printed label from the machine.
- 5 3. In a machine for printing and cutting labels from a strip of tape, cutting and printing mech-

anisms, a rotary platen beneath the printing mechanism, means for intermittently feeding the tape to the platen, whereby an impression may be made thereon by the printing mechanism, a plate disposed between the platen and the printing mechanism, and a plurality of resilient fingers secured to said plate and having their free ends yieldably holding the label in frictional contact with the periphery of the platen, whereby when the printing and severing operations have 10 been completed, rotation of the platen will eject the printed label from the machine.

5 JULIUS RUDIE.
